UNITED STATES PATENT OFFICE.

HELMER G. JOSEPHSON, OF EAST LYNN, MASSACHUSETTS, ASSIGNOR BY DIRECT AND MESNE ASSIGNMENTS, TO JOHN L. SHEVENELL, OF HAVERHILL, MASSACHUSETTS, AND HELMER G. JOSEPHSON, OF LYNN, MASSACHUSETTS, TRUSTEES.

SHOE-SHANK SUPPORT.

Application filed March 16, 1922. Serial No. 544,154.

To all whom it may concern:

Be it known that I, HELMER G. JOSEPHSON, a citizen of the United States of America, and a resident of East Lynn, in the county 5 of Essex and State of Massachusetts, have invented certain new and useful Improvements in Shoe-Shank Supports, of which the following is a specification.

This invention relates to shank supports 10 for boots and shoes and has for its object the production of a device of this character which may be cheaply constructed and easily applied to a boot or shoe and when applied will give the required support to the shank.

15 The invention consists of a support made of metal having strengthening depressions at opposite ends, that at the forward end having a greater depth than those at the rear end.

20 The invention further consists of providing the support with securing prongs extending upwardly from opposite ends thereof.

25 The invention further consists in certain novel features of construction and arrangement of parts which will be understood readily by reference to the description of the drawings and to the claims to be hereinafter given.

30 For the purpose of illustrating the invention, one preferred form thereof is shown in the drawings, this form having been found to give satisfactory and reliable results, although it is to be understood that 35 the various instrumentalities of which the invention consists can be variously arranged and organized, and that the invention is not limited to the precise arrangement and organization of the instrumentalities as herein shown and described, except as required by the scope of the appended claims.

Of the drawings:

Figure 1 represents a plan of a shank support embodying the principles of the present 45 invention.

Figure 2 represents a side elevation of the same.

Figure 3 represents a transverse section on line 3, 3 on Fig. 2, and

50 Figure 4 represents a transverse section on line 4, 4 on Fig. 2.

Similar characters indicate like parts throughout the several figures of the drawings.

In the drawings 10 is a metal plate curved 55 to fit the shank of a boot or shoe. One end of the plate 10 is provided with a deep V-shaped depression 11 extending toward the opposite end of said plate and dividing into two shallow depressions 12 forming a Y as 60 viewed in plan. These depressions 11 and 12 greatly stiffen the shank support, not only longitudinally but also laterally and cause it to retain its initial curvature. The V-shaped depression has a considerable depth 65 as this part of the shank support sustains the most strain and the edges of the support opposite the V-shaped depression are spaced apart a distance considerably less than the edges opposite the shallow depressions 12. 70 The edges of the wide portion are parallel and joined by inclined edges to the narrow portion, the edges of which are also parallel.

On either side of the depressions 11 and 12 and extending from one end of the plate to 75 the other are two outwardly extending flanges 13, which are adapted to bear against the inner sole of the shoe when positioned therein.

The shank support is provided with an 80 opening 14 therein in which a rivet may be positioned to secure the shank support to the shoe if desired.

The opposite ends of the shank support are provided with upwardly extending 85 V-shaped prongs 15 which are adapted to be inserted through the inner sole of the boot or shoe and then bent downwardly against the inner face of the inner sole to secure the shank support thereto. 90

This makes a very simple form of shank support having great rigidity and strengthened by the depressions 11 and 12 whereby its curvature will be maintained under all conditions. 95

By providing the securing prongs 15 formed integral with the plate 10, the shank support is complete in itself and may be easily secured in position without depending on other securing members. The downwardly extending V-shaped portion 11 has a considerably greater depth than the shallow depressions 12 as most of the strain upon the shank support comes at this point just in advance of the heel of the completed 100 shoe and requires a greater stiffening to retain the plate 10 in its original shape. In the forward end of the stiffener the de-

pressions are of less depth in order to avoid thickening of the sole of the shoe at this point, as otherwise the wearer of the shoe would be subjected to some discomfort when 5 the shoe was in use. The depressions 12, however, are of sufficient depth to prevent the stiffener from buckling.

The depression 11 has the greatest depth at its rear end and from a point where it is 10 divided into the depressions 12 gradually decreases in depth as shown in Fig. 1.

The stiffener has the greatest tendency to buckle at a point about midway of the length thereof and therefore at this point 15 the depression is widened and bifurcated, the two branches being angularly disposed relative to each other and then are parallel to each other and to the forward side edges of the stiffener. By constructing the stiffener in this manner the forward end of the 20 stiffener is made rigid without much depth and by joining the depressions 12 to the depression 11 by angular portions the stiffener is given increased strength midway of 25 its ends and is prevented from bending laterally.

It is believed that the operation and many advantages of the invention will be readily understood without further description.

30 Having thus described my invention, I claim:

1. A shank support for boots and shoes formed of metal with a V-shaped depression bifurcated at one end and having flat 35 portions laterally extending from said depression, the bifurcated portions of said depression being of less depth than the main portion thereof.

2. A shank support for boots and shoes 40 formed of metal with a V-shaped depres-

sion at one end and two semi-cylindrical depressions joined thereto at its opposite end, said semi-cylindrical depressions being of a gradually decreasing depth.

3. A shank support for boots and shoes 45 formed of metal curved to fit the shank of a shoe and having a V-shaped depression at one end and two semi-cylindrical depressions joined thereto at its opposite end having a depth less than said V-shaped depression and gradually decreasing in depth toward the end of the stiffener.

4. A shank support for boots and shoes 50 formed of metal with a deep V-shaped depression extending downwardly from one end and shallow depressions joined thereto at its opposite end, and having flat laterally extending portions curved to fit the shank.

5. A shank support for boots and shoes 55 formed of metal and curved to fit the shank having strengthening depressions, Y-shaped in plan, formed therein and provided with securing prongs extending upwardly therefrom at opposite ends.

6. A shank support for boots and shoes 60 formed of metal and curved to fit the shank having at one end a wide portion with straight parallel edges and near the opposite end a narrower portion with straight 70 parallel edges, said narrow portion having a deep V-shaped depression therein having parallel shallow depressions joined thereto and extending therefrom in the wide portion of the shank support.

Signed by me at 746 Old South Bldg., 75 Boston, Mass., this 13th day of March, 1922.

HELMER G. JOSEPHSON.
